UNITED STATES PATENT OFFICE.

WILLIAM A. GRISWOLD, OF NASHVILLE, TENNESSEE, ASSIGNOR TO GRAY & DUDLEY HARDWARE COMPANY, OF NASHVILLE, TENNESSEE, A CORPORATION OF TENNESSEE.

DESIGN FOR A STOVE.

44,197.

Specification for Design.

Patented June 17, 1913.

Application filed April 4, 1913. Serial No. 758,927. Term of patent 7 years.

To all whom it may concern:

Be it known that I, WILLIAM A. GRISWOLD, a citizen of the United States, residing at Nashville, in the county of Davidson and State of Tennessee, have invented a new, original, and ornamental Design for Stoves, of which the following is a specification, reference being had to the accompanying drawing, forming part thereof.

The figure is a view in elevation of a stove, showing my new design.

I claim—

The ornamental design for a stove, as shown.

WILLIAM A. GRISWOLD.
